CHILD'S SWING

Adrian Gil Spear, Jr., 17095 Dorset Ave.,
Livonia, Mich.

Filed Nov. 4, 1964, Ser. No. 82,470

Term of patent 3½ years

(Cl. D34—5)

FIG. 1 is a perspective view of a child's swing, embodying my new design.

FIG. 2 is a reduced bottom plan view thereof.

FIG. 3 is a front view thereof.

FIG. 4 is a rear view thereof.

I claim:

The ornamental design for a child's swing, as shown.
